US00D966291S

(12) **United States Design Patent** (10) **Patent No.:** **US D966,291 S**
(45) **Date of Patent:** ** *Oct. 11, 2022

(54) **DISPLAY SCREEN OR PORTION THEREOF WITH GRAPHICAL USER INTERFACE**

(71) Applicant: **Aristocrat Technologies Australia Pty Limited**, North Ryde (AU)

(72) Inventors: **Scott Olive**, Brookvale (AU); **Talles Vito**, Warriewood (AU)

(73) Assignee: **Aristocrat Technologies Australia Pty Limited**, North Ryde (AU)

(*) Notice: This patent is subject to a terminal disclaimer.

(**) Term: **15 Years**

(21) Appl. No.: **29/782,332**

(22) Filed: **May 6, 2021**

Related U.S. Application Data

(63) Continuation of application No. 29/725,591, filed on Feb. 26, 2020, now Pat. No. Des. 923,662.

(57) **CLAIM**

The ornamental design for a display screen or portion thereof with graphical user interface, as shown and described.

DESCRIPTION

FIG. 1 is a view of a display screen or portion thereof with graphical user interface showing our new design according to a first embodiment; and,

FIG. 2 is a front view of a display screen or portion thereof with graphical user interface showing our new design according to a second embodiment.

The outermost broken lines in the figures illustrate a display screen or portion thereof, and form no part of the claimed design. The remaining dashed broken lines in the drawings illustrate portions of the graphical user interface that form no part of the claimed design.

1 Claim, 2 Drawing Sheets
